His Attorney.

UNITED STATES PATENT OFFICE.

JOSEPH W. GOSLING, OF SCHENECTADY, NEW YORK, ASSIGNOR TO GENERAL ELECTRIC COMPANY, A CORPORATION OF NEW YORK.

DESIGN FOR A GLOBE.

51,064.

Specification for Design.

Patented July 24, 1917.

Application filed August 8, 1916. Serial No. 113,838. Term of patent 14 years.

To all whom it may concern:

Be it known that I, JOSEPH W. GOSLING, a citizen of the United States, residing at Schenectady, in the county of Schenectady, State of New York, have invented a new, original, and ornamental Design for a Globe, of which the following is a specification.

The accompanying drawing is a side elevation of my ornamental globe, comprising

a frame A provided with openings, in which are mounted panels B of light transmitting material.

I claim:

The ornamental design for a globe, as shown and described.

In witness whereof, I have hereunto set my hand this 4th day of August, 1916.

JOSEPH W. GOSLING.
